UNITED STATES PATENT OFFICE.

GEORGE B. ROSS, OF BUFFALO, NEW YORK.

CENTRIFUGAL OILER.

SPECIFICATION forming part of Letters Patent No. 288,667, dated November 20, 1883.

Application filed September 28, 1883. (No model.)

To all whom it may concern:

Be it known that I, GEORGE B. ROSS, a citizen of the United States, residing in Buffalo, in the county of Erie and State of New York, 5 have invented certain new and useful Improvements in Centrifugal Oilers, of which the following is a specification.

This invention relates to a certain means for oiling a loose pulley, or for other similar 10 purposes, by which the oil is forced onto the parts that require to be oiled by the combined action of centrifugal force and capillary attraction, all of which will be fully and clearly hereinafter shown by reference to the accompanying drawings, in which—

Figure 1 is a vertical central section through the complete device; also, a cross-section through the hub of the wheel or pulley to which it is attached, and through the shafting. Fig. 20 Fig. 2 is a horizontal section on line X X, Fig. 1. Fig. 3 is a cross-section through line Z Z, Fig. 4; and Fig. 4 is a side elevation of a portion of the body of the oiler, showing the openings through which the oil is carried by centrifugal force.

The oil-cup *a* is preferably made of glass, so as to be transparent; but it may be of any other suitable material, and is a hollow vessel, substantially in the form shown in Figs. 1 and 30 2; but any other suitable form may be used. The lower tubular portion, *a'*, is adapted to screw into a hub, *a''*, of a wheel or pulley, and is provided with a flanged portion, *a'''*, having a circular or annular groove, *a''''*, provided with 35 any suitable packing, *a'''''*, adapted to receive the lower glass portion, *b*, of the cup *a*.

b' represents the upper tubular portion having the openings *b''*, through which the oil is carried by centrifugal force. It is also provided with an annular groove, *b''''*, having a packing of rubber or other suitable material, *b'''''*. This groove is adapted to receive the upper portion, *b''''*, of the cup. The portion *a'* is provided with a screw portion, *c*, adapted to receive the part *b'*, which is provided with a nut-section, *c''*, by which it may receive a wrench to screw it in place. It is also provided with an internal screw, *c''''*, by which the hollow stopper *c'''''* is secured in position. (See

Fig. 1.) Through the part *a'* is a loosely-fitted 50 rod, *c''*, which is kept down against the shaft *c''''* by means of a piston, *c'''''*, and a spiral spring, *d*.

The operation of the invention is as follows: Oil being put into the cup *a* and the pulley or wheel being made to revolve, the oil is 55 thrown outward to the top *e* of the oiler, where it is forced in and closely around the rod *c''*, and from thence it is drawn down to the shaft by capillary attraction. When at rest and the oil-cup is in the position shown in Fig. 1, 60 the oil remains in the lower portion of the cup; but when the pulley to which it is attached is in motion the oil is forced to the top of the cup, as above mentioned.

In Fig. 1 I have shown a modified arrangement as an equivalent for the spring *d* for holding the rod *c''* to the shaft. It consists of the angular arm *g''*, jointed to the part *b'* by a pin, *g''''*. In this case the rod *c''* should be made a little shorter, so that the portion *i* of the arm 70 *g''* will rest upon it. *g''''* is a ball attached to said arm. It will now be seen that as the pulley revolves the ball will be thrown outward by centrifugal force from the center and cause the portion *i* to force the rod *c''* downward 75 against the shaft *c''''*. The oil-vessel is formed so that the portions *g* project down as near to the shaft as possible, and thereby increase its capacity. When a piston *c'''''* and spring is used, the metal at the bottom of the opening 80 can be closed slightly, as shown at *i'*, by a hammer, (or a tool made expressly for it,) so as to prevent the piston from coming out when the cap is removed for the purpose of refilling. The form of the oil-cup is adapted to permit 85 the centrifugal force to force all the oil to the piston or rod *c''*, from which it is taken by capillary attraction to the shaft, thereby insuring a continuous feed while the pulley is in motion, and, being closed air-tight, there is no 90 waste of the oil while the pulley is at rest. The spring or counterweighted arm *g''* is used to overcome the tendency of the centrifugal force to throw the rod *c''* out and thereby hold it in contact with the shaft.

I claim—

1. In an oil-cup, the tubular portion *b'*, provided with the openings *b''* near the center, in

combination with the rod c^4 , a spring for holding it down, and a pulley and shaft, substantially as and for the purposes described.

2. An oil-cup adapted to screw into the hub of a pulley or wheel, and provided with the tubular portion having portions $a' c'$ for holding it together, in combination with a loosely-fitted rod, a suitable device, substan-

tially as specified, for holding said rod to the shaft, and a hollow stopper, c^3 , for the purposes described.

GEO. B. ROSS.
